UNITED STATES PATENT OFFICE.

BERNARD JOSEPH McDONALD, OF PALMYRA, NEBRASKA.

RAILROAD CROSSING.

Application filed August 7, 1925. Serial No. 48,807.

This invention relates to improvements in railroad crossings and its main object is to provide a device wherein traffic is forced to a slow rate of speed or to come to a dead stop before crossing the railroad tracks.

Another object is to provide a device which can be readily set up at very little expense and serve its purpose in an efficient manner.

These and other objects will be apparent in the accompanying drawing and specification.

In the drawing:

Figure 1 is a plan view of the device designed in accordance with my invention.

Figure 2 is an end elevation of the device.

Figure 3 is a side elevation of the device.

In carrying out this invention I locate on each side of the highway 1 a series of aligned posts 5, the said posts 5 being spaced on each side of the railroad track 2 in such a manner as to permit traffic to go in either direction in between them. Cable fences 4 are secured to the posts 3, and to the posts 5 which are located at the sides of the highway 1. Fences 6 are provided for the purpose of separating traffic and preventing oppositely traveling traffic to go into each other's path; these said fences are spaced equally between the cable fences 4 and are of such a length as to cover the center of the highway for about one-

fourth of its total width. It will be seen that a machine approaching the railroad crossing 2 will be forced to slow down or to practically stop in order to pass between the fences 4 and 6.

While I have herein described a certain specific method of constructing and assembling the elements of my invention it is understood that the same may be varied in minor details not departing from the spirit of my invention as defined in the appended claim.

It is obvious that if a machine approaching one of the fences should not be slowed down or caused to pass around the fence, the inherent flexibility of the cable fence will be such as to bring the said machine to a stop without such a severe impact as would be the case in devices using rigid fences.

I claim:

In a railroad crossing in combination with a public highway, the combination with posts located in said highway on each side of the center, and posts located on each side of said highway, of cable fences secured to said posts and spaced in such a manner as to force traffic to travel at a low rate of speed when crossing the said railroad tracks.

In testimony whereof I affix my signature.

BERNARD JOSEPH McDONALD.
